VICTOR R. BROWNING, OF NOTTINGHAM, OHIO.

LIFTING-MAGNET.

No. 892,931.

Specification of Letters Patent.

Patented July 7, 1908.

Application filed December 14, 1906. Serial No. 347,749.

To all whom it may concern:

Be it known that I, VICTOR R. BROWNING, a citizen of the United States, residing at Nottingham, in the county of Cuyahoga and State of Ohio, have invented a certain new and useful Improvement in Lifting-Magnets, of which the following is a full, clear, and exact description, reference being had to the accompanying drawings.

10 This invention relates to lifting magnets, and has for its objects the production of a device of this character which will be simple and economical in construction, safe and effectual in operation, and one which, by simply varying the arrangement of the electrical connections in the magnet coils, may be used with currents of different voltages.

In the drawings forming a part of this application, Figure 1 is a top plan view of the 20 magnet with the cover for the switch casing removed. Fig. 2 is a transverse section taken through Fig. 1, substantially on the line 2—2, the eye-piece by means of which the magnet is lifted, being shown in elevation. Fig. 3 is a bottom plan view of the 25 magnet, and Fig. 4 is a diagrammatic view of the magnet coils and the means whereby these coils may be placed in parallel or in series, as desired.

30 Taking up a specific description by reference to the accompanying drawings, 1 represents the main member of the magnet, on the upper side of which there is provided at the center an eye-piece 2, by means of which the 35 magnet may be lifted. Projecting from the lower side of this member, at the center thereof, is the inner pole 3 of the magnet. Bolted or otherwise securely fastened to the outer periphery of the member 1, is the outer 40 pole 4, said pole being in the form of a ring, as shown in Fig. 3. These pole pieces of the magnet may be formed of any suitable magnetic material, but preferably of cast steel, that material having the necessary magnetic 45 qualities and possessing the requisite strength, it being understood that lifting magnets of this character are intended for taking up and transporting very heavy loads.

On its inner surface, and near the lower 50 edge thereof, the pole piece 4 is provided with an inwardly projecting ledge or shoulder 5, upon which rests an annular plate 6, said plate being formed of a suitable non-magnetic material, such as brass or copper. 55 This ring surrounds the inner pole piece, and

the lower side of said ring projects slightly below the lower end of said pole piece.

Secured to the lower side of the ring 6, and centrally located thereon, is a sub-pole 7, said sub-pole being preferably forged from 60 soft iron or steel. This sub-pole is directly beneath the inner pole 3 and, in effect completes said pole, although it is slightly separated therefrom, as shown, by a thin copper plate 8. This separation of the sub-pole 65 from the inner pole causes the magnet to lose its magnetization rapidly, so that it will release the body to which it is adhering more readily than it would otherwise do. The sub-pole may be connected to the ring 6 in 70 any suitable manner, as by rivets 9.

Inclosed within the annular space that surrounds the inner pole and that is formed by the said pole, the outwardly extending portion of the member 1, the outer pole 4 and 75 the ring 6, are the magnet coils 10 and 11, said coils being arranged concentrically about the inner pole.

The positive and negative terminals *a* and *b*, from the generator are connected to the 80 switch lugs 12 and 13, and to these switch lugs are likewise connected one end of each of the coils 10 and 11, the switch lugs being mounted on, and suitably insulated from each other by a block of insulating material 85 14, which is placed in a recess or chamber 15 that is formed on and within the upper surface of the magnet. This block 14 may be formed of any suitable material having the necessary insulating properties. This block 90 14 also carries two additional sets of switch lugs 16, 17 and 18, 19, the lugs 16 and 17 being suitably insulated from each other, while the lugs 18 and 19 are connected by a shunt wire 20. Pivoted to the lugs 16 and 17 is a 95 three-way switch 21. To the lugs 16 and 17 are connected the other ends of the magnet coils, it being remembered that one of the ends of said coils is respectively attached to the lugs 12 and 13. The recess or chamber 100 15 is preferably closed when in use by a cover 22, which may be pivoted to the magnet at one side of said chamber and secured by a suitable latch 23 at the opposite side.

When the switch is in the position shown 105 in Fig. 4, the current from the generator will pass through the wire *a*, to the lug 12, thence through the coil 11 to the lug 17, thence through the switch 21 to the lug 13 and to the terminal *b* leading to the generator. 110

The current, however, divides at the lug 12, part of the same passing through the switch to the lug 16, thence through the coil 10, to the lug 13 and the terminal *b*. It will be seen therefore that when the switch is in the said position, the coils 10 and 11 are in parallel. When, however, the switch is thrown over into engagement with the lugs 18 and 19, the current does not divide at the lug 12, but it all passes through the coil 11 to the lug 17, thence through the switch to the lug 19, through the shunt 20 to the lug 18, through the switch to the lug 16, and thence through the coil 10 and lug 13 to the terminal *b*. When in the latter position, therefore, the coils are in series. This arrangement of the coils is especially important, since the magnet may then be used upon circuits of different voltage; that is to say, if the generator furnishes current at 100 volts, the coils may be placed in parallel—while if the current is furnished at 220 volts, the coils will be connected in series, and the current flowing through each of the coils will be substantially the same as before.

By making the outer pole 4 separate from the member 1, a much better and sounder casting can be secured than when these parts are cast integrally. This is a very important factor in devices of this kind, as an imperfect casting will not only be unsafe in use, but its reluctance to the passage of the magnetic lines of force is greatly increased, thereby impairing the efficiency of the magnet.

While I have shown but two coils for the magnet, it is obvious that a greater number of such coils may be employed, if desired, and the following claims calling for a plurality of coils are not to be construed as limited to the two coils shown.

Having thus described my invention, I claim:

1. In a lift magnet, a main member having a central projection forming an inner pole of the magnet, a member surrounding said projection forming an outer pole member, a magnetic coil between said poles, and a sub-pole magnetically separated from the coils and the inner pole.

2. In a lift magnet, a main member having a central projection forming an inner pole of the magnet, a member surrounding said projection forming an outer pole of the magnet, a magnetic coil between said poles, and a sub-pole supported by the outer pole member magnetically separated from the coils and the inner pole.

3. In a lifting magnet, a main member having a central projection forming the inner pole of the magnet; a member surrounding said projection forming the outer pole, a magnetic coil for energizing the magnet, a sub-pole carried by said magnet in front of one of the poles thereof, and means for separating the said sub-pole from its adjacent

pole, whereby the demagnetization of the magnet is facilitated.

4. In a lifting magnet, a main member having a central projection forming the inner pole of the magnet; a member surrounding said projection forming the outer pole, a magnetic coil for energizing the magnet, a sub-pole carried by said magnet in front of the inner pole, and means for separating the said sub-pole from the inner pole, whereby the demagnetization of the magnet is facilitated.

5. In a lifting magnet, a main member having at its center a projection forming the inner pole of the magnet, the outer pole of the magnet surrounding said inner pole and secured to the said main member, said outer pole being provided with an inwardly turned ledge or shoulder, a plate of non-magnetic material resting upon said ledge or shoulder, a magnetic coil surrounding the inner pole of the magnet and resting upon said non-magnetic plate, and a sub-pole in front of said inner pole, and magnetically separated therefrom.

6. In a lifting magnet, a main member having at its center a projection forming the inner pole of the magnet, the outer pole of the magnet surrounding the inner pole and secured to the said member, said outer pole being provided on its inner side with a projecting ledge or shoulder, an annular ring of non-magnetic material supported upon said ledge, a sub-pole for the inner pole of the magnet, said sub-pole being attached to said ring, and being separated from the said inner pole, and a magnetic coil surrounding the said inner pole and resting upon said ring.

7. In a lifting magnet, a plurality of magnet coils for energizing the magnet, and means for placing said coils in parallel or in series as may be desired, whereby the magnet is adapted for use with currents of different voltage.

8. In a lifting magnet, a plurality of magnetic coils for energizing the magnet and a three-way switch connected with said coils and being adapted by its different positions to place said coils in parallel with each other or in series, whereby the magnet is adapted for use with currents of different voltage.

9. In a lifting magnet, electric terminals, a pair of switch lugs, 12 and 13, to which said terminals are connected, an additional pair of switch lugs, 16 and 17, a magnetic coil having its ends connected with the lugs 12 and 17, a second magnetic coil having its ends connected with the lugs 13 and 16, a third pair of switch lugs, 18 and 19, a shunt wire connecting the latter pair of lugs, and a switch connected with the pair of lugs 16 and 17, and adapted to be thrown into connection with either of the other pairs of lugs, whereby the coils may be placed in parallel or in series as desired.

10. In a lifting magnet, a main member having at its center a projection forming an inner pole piece, an outer pole piece surrounding the inner pole piece and secured to said main member, a plurality of magnetic coils concentrically arranged about the inner pole piece, and means for placing said coils in parallel with each other or in series as desired, whereby the magnet is adapted for use with currents of different voltage.

11. In a lifting magnet, a main member having at its center a projection forming an inner pole piece, an outer pole piece surrounding the inner pole piece and secured to said main member, a plurality of magnetic coils concentrically arranged about the inner pole piece, means for placing said coils in parallel with each other or in series as desired, whereby the magnet is adapted for use with currents of different voltage, and a sub-pole in front of the inner pole and separated therefrom, for the purpose specified.

12. In a lifting magnet, a main member having a projection at its center forming the inner pole of the magnet, an outer pole for said magnet secured to said member, said outer pole being provided with an inwardly extending ledge or shoulder, a ring of non-magnetic material resting upon said ledge or shoulder, a plurality of concentric magnetic coils surrounding the inner pole and resting upon said non-magnetic ring, and means for connecting said coils in parallel with each other or in series, as desired, whereby the magnet is adapted for use with currents of different voltage.

13. In a lifting magnet, a main member having a projection at its center forming the inner pole of the magnet, the outer pole of the magnets secured to said member, said outer pole being provided on its interior with an inwardly projecting ledge or shoulder, an annular ring of non-magnetic material surrounding the inner pole and resting upon the said ledge or shoulder, a plurality of magnetic coils surrounding the inner pole and resting upon the said ring, means whereby said coils may be placed in parallel with each other or in series as desired, whereby the magnet is adapted for use with coils of different voltage, and a sub-pole opposite the in-

ner pole and carried by said non-magnetic ring, said sub-pole being spaced from the said inner pole for the purpose specified.

14. In a lifting magnet, a main member having a projection at its center forming the inner pole of the magnet, the outer pole of the magnet secured to said member, said outer pole being provided on its interior with an inwardly projecting ledge or shoulder, an annular ring of brass surrounding the inner pole and resting upon the said ledge or shoulder, a plurality of magnetic coils surrounding the inner pole and resting upon the said ring, means whereby said coils may be placed in parallel with each other or in series as desired, whereby the magnet is adapted for use with coils of different voltage, a sub-pole opposite the inner pole and carried by said non-magnetic ring, and a thin plate of copper separating the sub-pole from the inner pole, for the purpose specified.

15. In a lifting magnet, a main cast-steel member having a central projection forming an inner pole, a cast-steel outer pole piece carried by the main member and surrounding the inner pole, said outer pole piece being provided with an interior ledge or shoulder, a brass plate surrounding the inner pole, and resting on said ledge or shoulder, a plurality of magnetic coils between said poles and resting on said brass plate, a switch chamber on said main member, a switch within said chamber, connections within the chamber whereby the switch may place said coils in parallel or in series, as desired, a forged sub-pole secured to the said brass plate below the said inner pole, and a copper plate resting upon the said sub-pole and separating the latter from the said inner pole, for the purpose specified.

16. In a lifting magnet, a main member supporting magnetic poles and a sub-pole magnetically separated from both the pole members.

In testimony whereof, I hereunto affix my signature in the presence of two witnesses.

VICTOR R. BROWNING.
